CLAIM

The ornamental design for a tree-branch shaped scouting camera, as shown and described.

DESCRIPTION

FIG. 1 is a front elevation view of a tree-branch shaped scouting camera showing our new design;

FIG. 2 is a top plan view thereof;

FIG. 3 is a bottom plan view thereof;

FIG. 4 is a rear elevation view thereof;

FIG. 5 is a left side elevation view thereof;

FIG. 6 is a right side elevation view thereof; and,

FIG. 7 is a front and left side perspective view thereof.

The broken lines depict portions of a tree-branch shaped scouting camera in which the design is embodied and form no part of the claimed design.
